RUBBER FOOTWEAR.

Application filed May 8, 1926. Serial No. 107,686.

This invention relates to rubber footwear and particularly to light overshoes or sandals, usually worn by women. The particular object of the invention is to devise a 5 light, serviceable overshoe which possesses certain structural features and advantages over previous forms of overshoes.

The form of sandal or overshoe shown in the present application is an all-rubber 10 overshoe made in such a way as to present an attractive appearance, the device being particularly attractive as a two-color sandal. In addition, it is so constructed that it may be turned inside out and worn with 15 either side showing so that by combining different colored rubber sheeting it is possible for the owner of the overshoe to change the color thereof to blend or match with varying colors of shoes or hosiery.

20 In order to accomplish this purpose, the structure of the overshoe is different from overshoes of the prior art, as will be explained, it being necessary merely to call attention to the fact that the shoe is preferably an all-rubber shoe, the parts being 25 made of laminated rubber sheeting so that in turning the shoe inside out the various color combinations may be obtained. It is also an advantage to have an overshoe, 30 which will turn inside out and be serviceable in either form, as such a device will permit of greater wear and longer life of the overshoe. For this reason, while specifically the invention relates to a multi-colored 35 overshoe, it is not necessarily so limited, but, in a broader aspect, is found in an overshoe of a single color. Other objects of the invention are to improve upon structural details of the overshoes as will be 40 pointed out.

Details of the invention are shown and described, but it will be understood that modifications and alterations may be made within the scope of the invention as set forth in 45 the claims.

In the drawings:

Figure 1 is a side elevation of a sandal or overshoe constructed in accordance with the invention;

50 Figure 2 is a section through the overshoe on the line 2-2 of Figure 1, showing in dotted lines the manner in which the overshoe may be reversed;

Figure 3 is a section through the instep or shank of the overshoe; and

55

Figure 4 is a section through the strap.

60

The overshoe is preferably constructed wholly of rubber sheeting of any preferred or suitable composition, and comprises an upper or vamp 1, a sole 2 and a strap 3 forming a continuation of the vamp and adapted to pass around the heel of the wearer.

65

The sole 2 of the shoe is made up, in the preferred form as illustrated, of layers of wear-resisting rubber 5 and 6 suitable for the tread, one of which forms the outsole and the other the insole of the overshoe depending upon the position in which the shoe is turned, both layers being suitable for either position. Between the soles 5 and 6 is located a middle sole 7, which may be made of rubber sheeting of good quality and great elasticity, being preferably a sheet of smoked plantation rubber or crepe rubber sheeting. This middle sole may be omitted 70 in less expensive overshoes. One of the soles 5 or 6 is folded around the middle sole, as shown in Figure 2. The surfaces of the several soles are preferably roughened because of the fact that they are made 75 of crepe rubber or in imitation thereof.

80

The upper or vamp 1 is shown in a plurality of layers of thin rubber sheeting. Two layers 10 and 11 are shown secured together, the lower edge of the vamp being 85 tucked in between layers of the sole. About the upper edge of the vamp one of the layers may be turned or rolled over the other as indicated at 12. This gives a finished appearance to the overshoe and affords a 90 method of obtaining a piping about the vamp which adds to the attractive appearance of the overshoe.

95

In order to secure the desired color effects, one of the soles and one of the layers of the vamp may be of one color and the other sole and other layer of the vamp may be of another color. Thus, the parts 5 and 10 may be of a light color and the parts 6 and 11 of a darker color. In the position 100 shown in full lines in Figure 2, the wearer will have a dark overshoe with an attractive light colored piping about the upper edge. This may match or "go well" with certain shoes or hose. Upon turning the 105 shoe inside out, a different colored overshoe

will be secured. By a selection of colors for the various layers, a wide variety of shades and combinations will be obtained. It is noteworthy that in either position a serviceable overshoe will be provided. The two treads or wearing layers 5 and 6 differ in this respect from the usual construction of a sandal of this type, which has a layer of fabric as its insole, which, if the overshoe were turned inside out, would be unsuitable for use as an outsole. It will also be noted that no fabric whatever enters into the construction of the overshoe. For this reason the overshoe will fit snugly and neatly and conform more readily to the outline of the shoe. Furthermore, the fact that there is no fabric on the inner surface of the vamp makes an overshoe which will not injure the most delicate slipper.

Various other structural features will be noted, including a special construction at the shank 15 by which the sandal is held up tightly against the instep and the penetration of water to the sole of the shoe is prevented. This comprises the addition of a folded rubber strip 16 about the edge of the sole as shown in Figure 3. This additional strip braces the instep and holds the shank of the overshoe in tight contact with the shank of the shoe, thus making a neat appearing shoe and keeping water out of the overshoe. It will also be noted that the strip 16 affords webs or reinforcements 17 at the angles where the strap is attached to the vamp, which holds the strap up and prevents its sagging and aids in fitting the overshoe. This adds to the appearance of the overshoe.

The strap is formed as an extension of the vamp, but it may be reinforced by an additional strip of rubber 18 extending from the vamp around the entire length of the strap. An additional insert 19 may extend partially around the strap and gives a further reinforcement at the heel. These reinforcements serve to hold the shoe firmly upon the foot.

It is believed that the advantages of the invention will have been made clear from the description which has been given. It is apparent that changes and modifications may be made within the scope of the invention as will be appreciated by those skilled in the art.

What is claimed is:

1. A light rubber overshoe of the heelless type, comprising a vamp composed of a plurality of layers of sheet rubber, a sole composed of a plurality of layers of wear resist-

ing rubber, and a middle sole of resilient rubber, the layers of the tread and vamp being of different colors, respectively, the shoe being thereby adapted to be turned inside out and worn in either position, whereby the color of the overshoe may be varied.

2. A light rubber overshoe of the heelless type, comprising a vamp composed of a plurality of layers of sheet rubber, and a sole composed of a plurality of layers of wear resisting rubber, the layers of the tread and vamp being of different colors, respectively, the shoe being thereby adapted to be turned inside out and worn in either position whereby the color of the overshoe may be varied.

3. A rubber overshoe having a vamp comprising two layers of rubber of different colors, one of the layers being rolled over the edge of the other and exposed, whereby the effect of piping is secured.

4. A light rubber overshoe, having a vamp comprising two layers of rubber of different colors, and a sole comprising two layers of rubber of different colors, one forming an outsole and the other an insole, the construction thereby permitting the overshoe to be turned inside out and worn in either condition so that the color of the overshoe may be changed.

5. A light rubber overshoe, having a vamp comprising two layers of rubber, and a sole comprising two layers of rubber, each of the last named layers being suitable as an outsole or an insole, the construction thereby permitting the overshoe to be turned inside out and worn in either condition.

6. A light rubber overshoe, having a vamp, and a sole comprising two layers of rubber, each of the last named layers being suitable as an outsole or an insole, the construction thereby permitting the overshoe to be turned inside out and worn in either condition.

7. A rubber overshoe of the heelless type, comprising a sole, a vamp and a strap, the sole terminating at the shank, and a reinforcing rubber strip enclosing the inner edge of the sole, the strip being extended at the angle between the strap and the vamp and adapted to brace the parts.

8. A rubber overshoe of the heelless type, comprising a sole, a vamp and a strap, the sole terminating at the shank, a reinforcing rubber strip enclosing the inner edge of the sole, the strip being extended at the angle between the strap and the vamp and adapted to brace the parts, and a reinforcement at the rear of the strap about the heel.
